UNITED STATES PATENT OFFICE.

CHARLES A. RITTER, OF CHICAGO, ILLINOIS, ASSIGNOR TO NESTOR JOHNSON MANUFACTURING COMPANY, OF CHICAGO, ILLINOIS, A CORPORATION OF ILLINOIS.

STRAP HOLDER.

1,412,967.

Specification of Letters Patent. Patented Apr. 18, 1922.

Application filed June 28, 1920. Serial No. 392,448.

To all whom it may concern:

Be it known that I, CHARLES A. RITTER, a citizen of the United States, residing at Chicago, in the county of Cook and State 5 of Illinois, have invented new and useful Improvements in Strap Holders, of which the following is a specification.

This invention relates to strap holders, particularly adapted for ice skates, and consists in the matters hereinafter described and more particularly pointed out in the appended claims.

In the accompanying drawings—

Fig. 1 is a side view of an ice skate with 15 shoe attached and showing a strap holder of my invention secured to the under side of the heel plate of said skate;

Fig. 2 is a rear view of the parts;

Fig. 3 is an enlarged fragmentary view 20 of the rear end of the skate, taken on line 3—3 of Fig. 2, with parts in section and parts in elevation; and

Fig. 4 is a fragmentary bottom plan view taken on line 4—4 of Fig. 3.

The ice skate shown in the drawing is of 25 the tubular type and has a runner 1, a front cup 2, a sole plate 3, and a rear cup 4 having at its upper end an integral marginal flange 5, which forms the heel plate of the 30 skate. These plates are substantially horizontal and are supported above the runner 1 by the cups 2, 4. The skate is securely fastened to a shoe, such as 6, by fastening members, such as rivets 7 inserted into the sole 35 of the shoe and heel portions of the shoe through holes provided for that purpose in the sole and heel plates of the skate, as customary in skates of this general character.

A separate strap 8, having a buckle 9, is 40 used to hold the rear of the skate more tightly and firmly against the heel of the foot than gained by the shoe alone. This strap is looped under the heel plate 5 to the rear of the rear cup 4 and encircles the 45 shoe on the outside thereof and extends over the instep of the foot, where it is tightened by the buckle 9.

To attach the strap 8 to the heel plate 5, there is applied to the under side of the heel plate, to the rear of the rear cup and in line 50 with the runner, a strap holder made in accordance with my invention. This holder is made of sheet metal, and comprises a body portion 10, in the form of a flat plate, preferably rectangular with one edge 11 concave

transversely to conform to the curvature of the rear cup and fit against the same, as shown in Figs. 3 and 4. The holder is secured to the heel plate by a single rivet or other fastener 12 and by fitting against the 60 rear cup 4 is held from turning about said rivet. The side portions of the plate 10 on opposite sides of the runner are cut or punched out and bent downward to provide depending loops 13, 13, through which extends the strap 8.

The strap holder 10, having two loops 13, 13 spaced apart, engages the strap 8 at two separated points in its length under the heel plate 5 and serves to keep a portion of 70 the strap under the heel plate substantially straight and thus gains more bearing of the strap on the heel plate than would be possible with only one loop. This adds to the effectiveness of the strap in holding the heel 75 of the shoe and skate tightly against the heel of the foot even though the shoe be of a size large enough to allow a relatively thick woolen or other sock to be worn. The loops 13, 13 being a rigid part of the plate 80 10, makes the use of only one fastening rivet necessary for both loops, this facilitating securing the loops to the skate and further permitting the holder to be sold as a separate piece and be applied to a skate 85 by the user or dealer when required.

I claim as my invention:

1. The combination in an ice skate, of a runner, a shoe plate supported above the runner by an upright member, said shoe 90 plate being rigid with the upper end of said member, and a strap holder comprising a flat plate secured to the under side of the shoe plate in line with the runner and having its side portions on opposite sides of 95 the runner cut out and bent downward to provide depending loops to receive a strap.

2. The combination in an ice skate, of a runner, a shoe plate supported above the runner by a cup, said shoe plate being rigid 100 with the upper end of said cup, and a strap holder comprising a flat plate secured by a single fastener to the under side of said shoe plate in line with said runner and having a concave edge to fit against said cup, 105 said holder plate having its side portions on opposite sides of the runner cut out and bent downward to provide depending loops to receive a strap.

3. The combination in an ice skate, of a 110

runner, a heel plate supported above the runner by a rear cup, said heel plate being integral with the upper end of the rear cup and projecting outward therefrom about the 5 sides and to the rear thereof, and a strap holder comprising a flat plate secured to the under side of the heel plate to the rear of said cup by a single fastener in line with said runner, said holder plate having one

edge engaging said rear cup and having its 10 side portions on opposite sides of the runner cut out and bent downward to provide two loops to receive a strap.

In testimony that I claim the foregoing as my invention, I affix my signature, this 15 25th day of June, A. D. 1920.

CHARLES A. RITTER.
